UNITED STATES PATENT OFFICE.

GEORGE GROOBAY, OF CHICAGO, ILLINOIS.

UNCOUPLING MECHANISM FOR RAILWAY-CARS.

SPECIFICATION forming part of Letters Patent No. 709,706, dated September 23, 1902.

Application filed November 8, 1901. Serial No. 81,619. (No model.)

To all whom it may concern:

Be it known that I, GEORGE GROOBAY, a citizen of the United States, residing at Chicago, in the county of Cook and State of Illinois, have invented a new and useful Improvement in Uncoupling Mechanism for Railway-Cars, of which the following is a specification.

My invention relates to an improvement in uncoupling mechanism for railway-cars, the object being to provide means for uncoupling from either side of the car by the use of a flexible connection, and an essential feature of my present invention consists in improved facilities for guiding and locking this flexible connection, and, further, my invention is adapted for use with the different leading types of car-couplings now in common use. In other words, my present invention is an improvement on the inventions disclosed in mechanical Letters Patent No. 612,588, granted to me October 18, 1898, and on Design Patent No. 32,641, granted to me May 8, 1900; and it consists in a plate provided with one or more sets of guide-sheaves arranged in pairs set at an angle to each other, in connection with a flexible connection attached to the uncoupling-pin and extending to one or both sides of the car over a pair or it may be a single one of a pair of these guide-sheaves.

The present invention further consists in a guide-plate provided with two pairs of guide-sheaves located in approximate alinement with or juxtaposition to the uncoupling devices of at least two different types of car-couplings in common use, in connection with flexible devices rove over the sheave or sheaves of the pair of sheaves nearest to the uncoupling means of the particular type of car-coupling used upon the cars.

My present invention still further consists in certain novel features of construction and combinations of parts, which will be herein-after described, and pointed out in the claims.

In the accompanying drawings, Figure 1 is a front elevation of a portion of a freight-car. Fig. 2 is an enlarged plan view of my improved guide-plate, showing two sets of guide-sheaves on the forward edge thereof. Fig. 3 is a transverse section on the line 2-2 of Fig.

Fig. 4 is a sectional view through one of the sheaves. Fig. 5 is a detail view of the locking device for securing the flexible con-

nexion, and Fig. 6 is a modification of the latter.

The guide-plate A, which constitutes one of the leading features of my present invention, is provided with four slightly-elongated transversely-disposed slots 11, by means of which the guide-plate is adjustably secured, through the medium of bolts 22, to the head-block 3 of the car. At the forward edge of the guide-plate two pairs of flanges 44 are struck up or cast, accordingly as the guide-plate is made of sheet metal or malleable iron. The flanges in each pair are disposed at an angle to each other, as clearly shown in Fig. 2. Sheaves 55 are supported on these flanges by means of bolts 66, upon which they turn. The sheaves are preferably made in two parts, as indicated in Fig. 4, secured together by rivets or bolts 77, and the groove at the periphery is as nearly circular as possible, with the opening at the outer edge just wide enough to afford clearance for the flexible connection to be hereinafter described. The object of thus disposing the sheaves at an angle in each pair is to adapt them for uncoupling means capable of being operated from either one or both sides of the car, and the object of the two pairs of sheaves is to provide for the use of at least two different principal types of car-couplings. For instance, with the Janney type of car-coupling the locking-pin is approximately in alinement with the left-hand pair of sheaves, as shown in Fig. 1, whereas the "Buckeye" uncoupling device is in alinement with the other set. Still a third set might of course be used at an intermediate point for the Gould type, for example.

B indicates the flexible connection, which may be of wire, rope, or made of chain. This is secured at one end to the uncoupling device, as shown in Fig. 1, and thence the flexible connection is rove over the left-hand sheaves of the left-hand pair to reach the corresponding side of the car and over the right-hand sheave of the same set to reach the opposite side of the car. This flexible connection is held at the outer end by a locking-plate 9. In this plate an inverted-L-shaped slot 10 is formed, through which the flexible connection passes loosely. In the lateral branch 12 of this slot a notch 13 is formed, and in this notch a link of the chain is dropped

or caught to secure the uncoupling device in its raised position when the cars are to be uncoupled. To release the uncoupling device, the chain is removed from this notch and 5 dropped into the lower end of the slot, where it may play freely and let the uncoupling device drop to its normal position. I apprehend that sometimes the center of a link may not come opposite this notch when the uncoupling device is raised and the connection is 10 taut, in consequence of which the uncoupling device would have to be lowered a trifle to bring a link in place to fasten. This would of course be fatal to the successful working 15 of the mechanism, because it would prevent the knuckle from opening. To obviate this, a second notch 14 is provided on a higher plane, as shown in the modification, Fig. 6. In that way if one notch is not in the proper 20 position it is probable the other will be, or, in other words, their relation in position to each other is such that one notch is pretty sure to hold the connection taut and the uncoupling device raised to its utmost.

25 From the foregoing it will be seen that the uncoupling may be accomplished from either side of the car and also without in any wise changing the car equipments. The uncoupling mechanism may be employed with the different types of car-coupling, thus saving time and expense and at the same time getting far better results than heretofore possible.

It is evident that slight changes might be made in the form and arrangement of the several parts described without departing from the spirit and scope of my invention, and hence I do not wish to limit myself to the exact construction herein set forth; but,

Having fully described my invention, what 35 I claim as new, and desire to secure by Letters Patent, is—

1. A guide-plate for cars, having two pairs of sheaves revolvably supported thereon, the sheaves of each pair being disposed at an angle to each other. 45

2. The combination with a car-coupling, an uncoupling device, and a head-block, of a guide-plate having two sets of guide-sheaves disposed in pairs at an angle to each other, a flexible connection rove over one or both 50 sheaves of either pair of guide-sheaves, said connection adapted to be attached at one end to the uncoupling device of the coupler, and means for fastening the opposite end of the flexible connection. 55

3. The combination with an uncoupling device, of a car-coupling, and a flexible connection, of a locking-plate having an inverted-L-shaped slot, the horizontal portion of which has means for fastening the connection. 60

4. The combination with an uncoupling device, of a car-coupling, and a flexible connection, of a locking-plate having an inverted-L-shaped slot with two notches in different horizontal planes to lock the connection. 65

5. The combination with a car-coupling, and an uncoupling device, of a guide-plate having two sets of guide-sheaves disposed in pairs at an angle to each other, a flexible connection rove over one or both sheaves of either 70 pair of guide-sheaves, said connection adapted to be attached at one end to the uncoupling device of the coupler, and means for fastening the opposite end of the flexible connection. 75

In testimony whereof I have signed this specification in the presence of two subscribing witnesses.

GEORGE GROOBAY.
